SIMULATED TREADED VEHICLE

Leo V. Jacobson, Webster Groves, Mo.

Application April 5, 1950, Serial No. 154,184

1 Claim. (Cl. 272—1)

1 This invention relates to a toy and in particular to an ambulatory, but unwheeled, toy.

One of the objects of this invention is to provide a new toy which may safely and easily be operated by any child able to crawl, but which may be used by children of any age.

Another object is to provide a toy which is adapted to many uses, both ambulatory and stationary, within the ingenuity of children.

Other objects will be apparent to those skilled in the art when the following specification is read in connection with the accompanying drawings.

In accordance with an illustrative embodiment of this invention, an endless track is provided, flexible longitudinally and of such construction that a child within the track, when the track is in its horizontal position, can support the weight of the track above him and propel the track along the ground. At the same time, the track is constructed to be sufficiently rigid transversely as to be self-supporting. This rigidity prevents the device from collapsing about a child within it and allows the use of the device as a vertical-walled enclosure.

In the accompanying drawings:

Figure 1 is a perspective view showing one embodiment of this invention being propelled by a child.

Figure 2 is a perspective view showing a slightly different embodiment of the device shown in Figure 1, showing a vertical-walled enclosure.

Figure 3 is a sectional view taken along the line 3—3 of Figure 2.

Figure 4 is a plan view showing one surface of a blank suitable for use in forming the device of this invention.

Figure 5 is a plan view of the reverse side of the blank shown in Figure 4; and

Figure 6 is a sectional view showing another embodiment of this invention.

One illustrative embodiment of this invention is shown in use in Figure 1. As shown in that figure, a track 1 is segmented by score lines 2 to provide in effect a series of parallel transversely-extending strips 3. The margins of the exterior surface 5 of the track 1 are printed with simulated treads 6. Intermediate these treads 6, transversely, are printed cannon 7. In the embodiment shown in Figure 1, ports 8 are provided which coincide with the muzzles of the cannon 7. The embodiment of this device shown in Figure 2 differs from the embodiment shown in Figure 1 in that no ports 8 are provided in the former.

In both the embodiments shown, Figure 1 and 55

2 Figure 2, the track 1 is constructed from a blank 12, the ends 9 of which are secured by an adhesive strip 10, as is shown in particular detail in Figure 3.

In Figures 4 and 5, the blank 12, from which a track 1 similar to the device shown in Figure 1, may be assembled, is shown. Such a blank may be made from a material such as corrugated board. It has been found that a corrugated board, known in the art as "C-flute" board, is particularly well-adapted to such use. It is to be understood, of course, that this invention is not limited to this particular material. It has been found that a blank on the order of twenty-four inches (24") wide and eight feet (8') long is suitable for producing a track which can be used by children of average height between the ages of two and ten, with some variation both ways.

When cardboard or an equivalent relatively thin material is used to form a track, the score lines 2 are preferably made on the inner surface only. This tends to give a certain amount of support longitudinally so that the track does not rest entirely on the child's back. This is shown in Figure 1. Entrance to the device is also thus facilitated. However, the weight of a corrugated track distributed over the child's back, when the score lines have weakened, or when the scoring is made on both sides, is practically negligible.

In Figure 6, an embodiment of this invention is shown in which strips 15 of material, which may be relatively rigid, are mounted upon a flexible, smooth-surfaced member 16. In this embodiment, the strips 15 are mounted on the external face of the track so that the child does not pinch his fingers between the strips when crawling. A similar construction, i. e., with the strips on the external surface, can be applied when the strips are integral with the backing as when the strips are formed by a molding or scoring process, when the material is of such a substantial thickness that a child's fingers can be pinched between the strips.

It is apparent that numerous suitable materials are available for this device within the scope of this invention. In the embodiment shown in Figure 6, for example, light wood slats, or aluminum, or other metal strips, plastics or even weighted cloth may be used for the transverse strips mounted on fabric or heavy paper backing.

Light rubber compositions may be molded or scored to form either an embodiment similar to that shown in Figure 6 or similar to that shown

3

in Figures 1 and 2. Such materials may be scored on the inside or outside surface or, as has been suggested with respect to the corrugated board, on both surfaces.

While in the embodiment illustrated in Figures 1 and 3, an adhesive tape is shown as the end-fastening means, it is to be understood that various other methods of securing the two ends of a blank are contemplated, such as a splice of the blank material itself, or the use of staples, etc. The track may be made in one piece, so that no binding is necessary.

It can be seen that the track may be rolled upon itself for shipping or storage. When an unassembled blank is used, the blank may be rolled from end to end to form a compact bundle.

In operation in the embodiment of the invention in which the device is assembled from a scored corrugated board blank, the ends of the blank are joined in a suitable manner, as by tape, which may be gummed or pressure-responsive, with the printed side of the blank out, and the scored side in. In those embodiments of the invention in which it is desirable that the scored or slatted sides be out, the track is assembled to so provide. In those embodiments in which the track is fabricated as a continuous belt, without free ends, no assembly is, of course, necessary.

The track is laid horizontally with one of its exterior surfaces flat on the ground. The child, assuming a position within the track, such as, for example, that shown in Figure 1, can propel the track by simply crawling forward. This produces a motion within the track surprisingly like that of a "tank." Even a very small child can propel the device over obstacles lying in his path, and even, with some practice, on stairs and the like. Almost innumerable methods of propelling the track will occur to the child, such as somersaulting within it, standing or crouching, et cetera. By lying transversely of the track, within the track, two or more children can roll simultaneously to produce motion.

The track can also be used as a fort, house or play pen, by simply turning it to a vertical position as shown in Figure 2. In that position, the enclosure may be made to assume various configurations.

The cannon shown in the embodiments of Fig-

ures 1, 2 and 4 are so printed as to appear to shoot outwardly from any position of the track at which they are visible. The ports which may be provided allow greater visibility for the child and add realism to the effect of the cannon. It is to be understood that other suitable pictures may be printed in place of the cannon, or in addition thereto, or the printing may be omitted.

Thus it can be seen that a new, useful, entertaining, safe, ambulatory toy is provided which is adapted to numerous uses as a toy and which provides healthful exercise for its users.

Having thus described the invention, what is claimed and desired to be secured by Letters Patent is:

A toy, simulating a vehicle equipped with treads, to be propelled by a child therein consisting of a band formed into a closed loop track and made up of transversely extending, flexibly connected segments, the track being flexible longitudinally and self-supporting transversely, being light in weight and of sufficient width and length to accommodate the body of a child in the interior thereof, the outside surface of said loop track being imprinted to simulate the usual external characteristics of said vehicle, said characteristics including ports such as the gun ports or observation ports of a war tank, and said track having holes therethrough intermediate its edges, said holes being spaced longitudinally along said track and forming ports coincident with said imprint.

LEO V. JACOBSON.
